United States Patent Office

Des. 217,736
Patented June 2, 1970

217,736

APPLICATOR TIP CLEANING UNIT

Arnold R. Marsee, Allen, Ohio, assignor to Artex Hobby Products, Inc., Lima, Ohio, a corporation of Ohio

Filed Jan. 6, 1969, Ser. No. 15,207

Term of patent 14 years

Int. Cl. D15—06

U.S. Cl. D49—1

FIG. 1

FIG. 2

FIG. 4

FIG. 3

FIG. 1 is an exploded view showing the unit with its cover removed,

FIG. 2 is a top plan view,

FIG. 3 is a bottom plan view; and

FIG. 4 is a side elevational view of the unit including its cover.

I claim:

The ornamental design for an applicator tip cleaning unit, substantially as shown and described.
